UNITED STATES PATENT OFFICE.

ALBERT CLÉRET, OF PARIS, FRANCE.

RESILIENT WHEEL.

1,105,321.

Specification of Letters Patent. Patented July 28, 1914.

Application filed December 16, 1912. Serial No. 737,010.

To all whom it may concern:

Be it known that I, ALBERT CLÉRET, citizen of the French Republic, residing at Paris, Department of the Seine, in France, have invented certain new and useful Improvements in Resilient Wheels; and I do hereby declare the following to be a full, clear, and exact description of the invention, such as will enable others skilled in the art to which it appertains to make and use the same.

The present invention has for its object a resilient wheel characterized by the employment of one or more parallel cables arranged upon supports fixed to the periphery of an inner rim. Rollers integral with an outer rim bear upon these cables.

The cable or cables are preferably not resilient but the supports fixed to the inner rim may be resilient to absorb the shocks. As a result of this arrangement the shocks received by the outer rim are transmitted to the cable and absorbed by the supports. The inner rim is driven by the outer rim by means of springs or resilient bands. This arrangement presents the advantage of distributing the strains efficiently over the various resilient portions of the whole, thus affording great flexibility in the suspension.

The invention is illustrated in the accompanying drawing, in which:

Figure 1 is a longitudinal section of a portion of a wheel embodying the invention. Fig. 2 is a section on the line A—A in Fig. 3. Fig. 3 is a section on the line B—B in Fig. 1. Fig. 4 is a section on the line C—C in Fig. 1. Figs. 5 and 6 represent details respectively of one of the cable supports and of one of the sliding blocks. Fig. 7 illustrates a method of support, the cable being divided into lengths. Fig. 8 illustrates a modified form of the invention. Fig. 9 is a section on the line D—D in Fig. 8. Fig. 10 is a section on the line E—E in Fig. 8. Figs. 11 and 12 are respectively an elevation and a plan illustrating the manner of attaching the cables.

The resilient wheel represented in Fig. 1 comprises two parallel cables or bands 1, 1; these cables are rigid and preferably endless and pass over rollers 2, 2 arranged upon supports 3 of india rubber or other appropriate material. The support proper is fixed to the inner rim 4 in any appropriate manner; by way of example a method of mounting has been represented in which

the support 3, presenting the form of a cylindrical sector is arranged upon a wedge 3' of corresponding form and comprises a projection 6 of the same dimensions as the wedge. A metal frame 5 confines both the projection and the wedges and is fixed to the rim 4 by means of screws. A notch 7 is provided at the upper part of the support 3. A shaft 9 to which the rollers 2 are fitted is held in place and supported by metal disks 8. This shaft 9 rests in two slots 10 formed in the disks 8 which are fixed to a strip of metal 11 presenting exactly the same form as the shock absorber or support 3 of india rubber and ending on each side in beadings 11'; a bolt 12 passes through the support 3 and the two disks 8 and maintains the whole in place.

The outer rim 13 carries rods 14, 15 which receive rollers 16, 17 serving to facilitate the slip on the cables 1, 1. The rods 15 are prolonged toward the center, pass through openings 18 in the inner rim 4 and then enter the aperture 19 in a block 20 which serves to maintain the two rims 13 and 4 in the same plane and drive the outer rim 13 without impairing the flexibility and resiliency of the system. The block 20 is composed of two right-angled triangular prisms assembled by their hypotenuses and held together by two screws 21. The aperture 19 is formed in a direction perpendicular to the joint face. The upper and lower edges of the aperture 19 may be rounded, as shown in Fig. 1, to permit of the variations of angle of the rod 15 with the blocks 20 under the influence of vibration during running. In each of the triangular prisms cavities are formed for the reception of rollers 22 serving to guide the rod 15 and of rollers 22' serving to drive it. The shafts of these rollers are held in place by bringing the two triangular prisms together.

The block 20 runs between two slideways 23 fixed by their extremities to the inner rim 4 by means of bolts 24 which pass through a part 24' fixed to the rim. These same bolts serve to support the plates (Fig. 4). The slideways 23 are complementary in shape to the block 20. They receive spiral springs 25 holding the block resiliently in place, their tension being calculated in such a manner as to obtain the drive of the rod 15, while nevertheless permitting this rod to move under the influence of shocks and vibrations. The outer rim 13 receives the shocks, vibra-

tions, and so forth and transmits them to the cables through the rods 14, 15. When the cables 1, 1 are deflected a diminution of the circumference of the circle circumscribed at 5 the apexes of the polygon that they form will result in a compression of the resilient supports 3 which thus absorb the vibrations.

The cables 1, 1 are constituted by bands of metal or any other appropriate material 10 such as silk, or the like which is woven or twisted to form cables. Their length should be less than the perimeter that they are intended to occupy, in such a manner that they can be made perfectly taut; the tension given 15 to the two cables should be equal.

The cables might be divided into two or more lengths connected at their extremities to two supports which may be adjacent or not. The ends of these lengths might also 20 be fixed to resilient supports, as shown in Fig. 7. The cables 1, 1 are fixed to the ends 26, 26' of two bent levers 26', 26' each of which rocks about a pivot 27. These levers pass through a transverse slot 28 formed in 25 the inner rim 4 in such a manner that the pivot 27 is in the same plane as and slightly beneath the slot in which it is supported by small bearings fixed to the rim. Each of the horizontal arms 26' rests upon one or more 30 spheres or blocks 29 of india rubber or other resilient material supported by a metal casting 30' ending in flanges 30' which are brought more or less close to the rim by acting upon tightening bolts, whereby the tension 35 of the cables can be regulated. Each deformation of the cable 1 is transmitted by the vertical arm 26 and then by the horizontal arm 26' to the sphere or block 29 of india rubber which absorbs the shock.

40 When the rods 14 and 15 occupy the middle of the outer rim 13 (Figs. 2, 3 and 4) and the rollers 16 and 17 are arranged symmetrically on either side, the wheel spokes are omitted and replaced by two frusto conical plates 31 and 31' whose edges supporting the inner rim 4 are bent to form flanges 32 and 32'. One of these plates is detachable—the plate 31' for example; this detachable plate is arranged on the outer face of 45 the wheel. The other plate 31 may be permanently fixed in position. The detachable plate 31' carries parts 33 serving to close the passage for the introduction of the rods 15 into the admission orifices 18 of the inner rim 4.

The section of the outer rim 13 may be semicircular and upon each side of it two india rubber cheeks 34, 34' are fixed by any convenient means. The inner surface of 60 these cheeks is coated with an unctuous product so that it can slide over the edge 32 of the plates 31, 31', so that these cheeks form a dust and moisture excluding joint for the system. A ring 35 of rubbered canvas or of 65 thin flat corrugated or folded india rubber

can be fixed on one side to the edge of the plate and on the other to the extremity of the cheek and which moves in the space 35' (Fig. 3).

The wheel is assembled in the following 70 manner: In the first place the outer rim 13 is fitted, each of the rods 15 being opposite its orifice 18 formed in the inner rim 4; upon exerting pressure the rods enter the passage; the blocks 20 are fixed after each of 75 the rods 15 has been introduced into its opening 19 and then the plate 31' is arranged in place and fixed by means of bolts; the parts 33 are then made to close the admission orifices 18 and finally the cheeks 34 and 34' are 80 fixed to the outer rim 13.

In the arrangement illustrated in Fig. 8, the suspension is provided for as before by means of cables 1, which are preferably not resilient. The supporting blocks 3 are similar to those described above and are arranged in the same manner around the inner rim 4. The rods 14 support the outer rim which may be provided with a tire 39. Said rods 14 are not continued below the inner rim and it is consequently unnecessary to provide openings in this rim. It may be of any ordinary type. As in the preceding case, the outer rim 13 is prolonged on both sides of the inner rim by cheeks 34 and 34', 90 which in this case are of metal and of sufficient width to insure that they shall not extend beyond the inner rim during the largest displacements experienced by the outer rim. 95

100 Stays 40 unite the two cheeks 34 and 34' and maintain their spacing. Upon the lateral faces of the wooden hoop 41 which supports the inner rim 4, balls 42, 42' are arranged at intervals; these balls permit of the displacement of the outer rim 13 relatively to the inner rim 4 with a minimum of friction and oppose any lateral displacement of the two rims.

105 The two rims are connected by means of endless bands 43 of india rubber passing over rollers 44 and 47 one of which is connected with the inner rim and the other with the outer rim. Each of the rollers 44 is mounted upon two bell-crank levers 50 pivoted on the pivot of the rollers their convexity being directed toward the center of the wheel. Each of the rollers 47 is similarly mounted on two parallel levers 46, the concavity of which is directed outwardly. 110 These rollers are pivoted to pivots 45 mounted on the rods 14 of the outer rim which also support the rollers on which the cables 1 slide. Each of the pivots 45 is fixed to the corresponding rod 14 by means of plates 51 riveted on either side of this rod and to which a band of V-shaped steel 48 is pivoted at 52; this band is fixed to the other extremity of the plates 51 by means of a spring pin 53. Between the parts 14 and 48 the pivot 115 120 125 130

45 is held; this pivot carries the cable rollers and the crescents 46. The bands 43 of india rubber produce the displacement of the two rims one by the other, with the 5 maximum flexibility. In order to prevent the rollers from coming into contact with the opposite rim in the case of breakage of the cables or of an excessively violent shock, a certain number of india rubber bands 54 10 can be arranged upon the inner rim 4 between the supports 3. The rings 35 and 35' of india rubber or of corrugated fabric are provided at each extremity with a beading. These beadings are introduced by pressure 15 into metal angle pieces 55 and 56, of which 55 occupies the lateral face of the circle 41 carrying the rim while the other 56 occupies the lower part of the metal cheek.

In order to assemble the wheel, the cables 20 1 are stretched on the blocks 3 and the crescents with their drive rings are arranged upon the pivots and the outer rim with one of the cheeks 34 or 34' is introduced. The rods 14 are passed between the two cables, 25 the pins which fix the plates 48 being released. The pivots are arranged in place, the bolts are closed and thereupon the second cheek is fixed; the corrugated rings are fitted and the stays are bolted. Each of the 30 cables 1 can be replaced by a cable 1' (Figs. 11 and 12) of circular section which passes around the wheel a number of times, the rollers being channeled in this case.

Each length of the cable 1' is engaged in 35 small rollers 57, 58 mounted upon a cross piece 59 which is capable of inclination. The two cross pieces 59 are connected by two cables 60 resting upon the rollers of a block 3. The extremities of the cable, after 40 passing over the rollers 57 and 58 then pass through the inner rim 4 on which they are

fixed to a tensioning system arranged externally.

The invention is not limited to the constructional forms represented in the drawings. The inner rim in particular might be modified or even dispensed with if the supports were held by other appropriate means. The form of wheel described above might also be adapted to shock absorbers, pulleys 50 and so forth.

Claims:

1. A resilient wheel comprising an outer rim, an inner rim, resilient supports carried by one of said rims, inelastic means encircling said supports to transmit pressure to all of said supports simultaneously, and means to support the other rim on said means whereby road shocks are transmitted through the intermediary of said means to 55 said supports.

2. A resilient wheel comprising an outer rim, an inner rim, resilient supports carried by said inner rim, an encircling inelastic band surrounding said supports, and inelastic means to support the outer rim on said band. 65

3. A resilient wheel comprising an outer rim, an inner rim, resilient supports carried by one of said rims, inelastic means to transmit pressure to all of said supports simultaneously, and means to support the other rim on said means whereby road shocks are transmitted through the intermediary of 70 said means to said supports. 75

In testimony whereof I affix my signature, in presence of two witnesses.

ALBERT CLÉRET.
